UNITED STATES PATENT OFFICE.

GUSTAV SCHMIDT, OF CINCINNATI, OHIO, ASSIGNOR TO THE CINCINNATI BUTCHERS' SUPPLY COMPANY, OF CINCINNATI, OHIO, A CORPORATION OF OHIO.

REFRIGERATOR DISPLAY CASE.

Application filed December 30, 1927. Serial No. 243,559.

My invention relates to refrigerator display cases arranged to exhibit goods and to subject the same to cooling action while being displayed.

5 My invention is exemplified as employed in connection with a refrigerator display case arranged to rest upon the floor of the store, and provided with a bottom adjacent said floor, with a serving counter top, over 10 which the goods are arranged to be served to the customer, and a rear wrapping counter located at a lower level than said serving counter top.

It is the object of my invention to so construct a refrigerator display case as to provide a maximum amount of display space, and to bring substantially all portions of the display space to the view of the customer in novel manner; and, further, to provide 20 novel arrangement of means whereby said goods are readily accessible to the attendant or salesman.

It is the object of my invention, further, to provide a display case with full view exposure transparent closures extending upwardly and beginning adjacent to the bottom line of the case and arranged side by side in the front of the case; further, to provide substantially full view end closures 30 and full view front closures extending from substantially the bottom line of the display case to the serving counter top thereof, and forming substantially continuous exposure of the interior of the case for substantially 35 full view of the contents of said display case; and, further, to provide a refrigerating element arranged crosswise in the interior of the display case, whereby to divide said interior into a plurality of display 40 spaces arranged side by side.

It is the object of my invention further to provide the upper portion of the display case between the wrapping counter and the serving counter top with slopingly arranged 45 doors for convenient access of the attendant into the interior and for providing an upper space in the display case which converges toward the top; and, further, to provide a refrigerating element arranged cross- 50 wise of the interior of the display case having an upper portion, the upper rear edge portion of which is slantingly arranged to correspond with the general slope of said rear doors.

55 It is the object of my invention further to

provide novel means in a full view refrigerator display case of the character mentioned whereby to support the goods; further, to provide novel means for supporting the goods and novel arrangement of doors permitting their convenient removal from the interior of the case; and, further, to provide a novel arrangement of shiftable shelving, and novel means for shifting said shelving between said refrigerating elements for ready access to the goods.

The invention will be further readily understood from the following description and claims, and from the drawings, in which latter:

70 Fig. 1 is a perspective view of my improved device, partly broken away.

Fig. 2 is a rear elevation of the same.

Fig. 3 is a horizontal cross-section, taken in the plane of the line 3—3 of Fig. 6, showing the relation of the refrigerating element, 75 the shiftable goods shelves, the doors and the front transparent closures.

Fig. 4 is a longitudinal section of the same taken in the plane of the line 4—4 of Fig. 6.

Fig. 5 is a perspective view of a detail of the same, partly broken away, showing the means for supporting the shelves.

Fig. 6 is a vertical cross-section of my improved device taken in the plane of the line 6—6 of Fig. 4.

Fig. 7 is a cross-section of a detail of my improved device taken in the plane of the line 7—7 of Fig. 6, and partly broken away, 80 showing the supporting means for the shiftable shelf, and;

Fig. 8 is a cross-sectional detail of the same, taken in the plane of the line 8—8 of Fig. 7, partly broken away showing the 85 shiftable shelf in normal position in full lines and in tilted position for removal of the same in dotted lines.

The refrigerator display case comprises a base 21, forming a bottom wall, front corner posts 22 which slope slightly rearwardly toward their tops, intermediate front posts 23, correspondingly slanted, and a top longitudinal stringer 24 for forming front display openings 25, 26, which display openings extend substantially throughout the length and height of the case for full exposure of the interior of the case through its front. The framing of the case further comprises rear end posts 31 and intermediate rear posts 32,

at the top of which there is a rear counter 33, which may be designated a wrapping counter. Openings are thus formed between said uprights, the base of the case and said 5 wrapping counter, arranged to be closed by doors 34, respectively supported on the rear posts by suitable hinges 35 and held in closed positions by latches 36.

Forwardly and upwardly slanting end 10 pieces 41 connect at their bottoms with the rear end posts 31 and at their tops with cross-pieces 42, the latter connecting with the front end posts 22, for forming each of the ends of the case with a display opening 15 43 extending substantially throughout the depth of the case and from its bottom past the wrapping counter to substantially the top of the case.

A longitudinal stringer 45 connects the 20 upper corner between the upwardly forwardly sloping end-piece 41 and the top cross-piece 42, at the respective ends of the case, stiffening braces 46 being slantingly located between the structure of the wrapping counter and said longitudinal stringer 45, for steadyng and stiffening said longitudinal stringer.

An upwardly forwardly sloping rear wall 30 of the case is thus formed, in which there is a door opening 47, which may extend throughout the length of the case. Runways are located on the lower and upper walls of said door opening for upwardly forwardly sloping doors 51. There is preferably a pair 25 of the stiffening braces 46, located under the respective ends of the middle one of the doors 51, and form stops for the doors adjacent to said middle door. The doors comprise lower sliding doors and upper sliding doors. The lower sliding doors slide under 40 the end ones of the upper sliding doors, and the upper sliding doors slide over the lower sliding doors.

The inner edges of the upper and lower 45 walls of said opening are provided with flanges 52, forming runways for the inner doors, and the outer doors are provided with flanges 53 coacting with the upper and lower walls of said opening for forming runways 50 for the outer sliding doors.

An upper display opening 55 is provided in the top of the case between the forward stringer 24, the rear stringer 45 and the end cross-pieces 42, through which the interior 55 of the case may also be viewed. The opening thus formed is arranged to be sealed by transparent closure plates 56 and a top transparent plate 57, having dead air spaces 58 between them, for resisting transference of 60 heat between the inside and the outside of the case. This top of the case forms a delivering or serving counter for the attendant, whose position is in rear of the case.

The front openings 25, 26, are sealed by 65 transparent closure plates 61, between which

there are dead air spaces 62, for resisting transference of heat between the inside and the outside of the case. The middle one of the front openings is shown of greater length than the length of the end openings, as an 70 example, substantially twice the length, for enhancing the exposure effect of the interior of the case to the view of the customer at the front of the case.

The end openings are sealed by transparent 75 closure plates 65, having dead air spaces 66 between them, for resisting transference of heat between the inside and the outside of the case.

The doors 51 are provided with display 80 openings, sealed by transparent closure plates 68, having dead air spaces 69 between them, for resisting transference of heat through said doors.

The transparent closure plates are preferably 85 sheets of glass. This improved construction exposes the interior of the case to the view of the customer from its front, its ends and its top, throughout substantially the height, the length and the width of the 90 case, so as to fully expose the contents of the case, and the transparent closure plates in the doors 51 additionally expose the contents of the case to the salesman.

The base of the case and the balance of 95 the framework thereof and the main doors are suitably heat insulated in any desirable manner, not more particularly shown because the providing of such insulation will be readily understood by those skilled in 100 the art.

Refrigerating elements are disposed in upright manner crosswise of the case and form partitions, which divide the interior of the case into display compartments. One or 105 more of the refrigerating elements may be employed. The refrigerating elements may be of any suitable kind for employing any kind of refrigerant. Two of these refrigerating elements are shown at 71, 72, for 110 dividing the case into compartments 73, 74, 75, for the goods, such as meats, sausages and other food products. The middle compartment is shown wider than the end compartments, being shown substantially twice 115 as wide as each of the end compartments.

The refrigerator elements are shown as pipes, through which the refrigerant, such as brine, ammonia, or other fluid refrigerant, may flow or be forced for causing cooling or refrigeration in the interior of the case.

The refrigerating elements are shown as 120 located in rear of the posts 23, between the transparent display openings at the front of the case, and in front of the end ones of the intermediate posts 32, so as to locate said refrigerating elements between the main doors at the rear of the case. The front edges of the refrigerating elements are located 125 behind the intermediate posts 23 be-

tween the front display openings so as to obscure the same from direct observation by the customer.

These refrigerating elements are respectively shown as pipes arranged in narrow loops 78, the loops having preferably substantially similar major axes in the main portion of the case, to which access is had by means of the main doors 84, the loops 10 gradually decreasing in length along their major axes in the upper contracting portion of the case toward the top of the interior of the case.

The loops are supported by uprights 79, 15 80, there being a pair of these uprights adjacent each end of the refrigerating element. Each pair of uprights is connected by a cross-strip 81, forming a foot for the uprights on which the uprights rest on the 20 base. The respective loops are secured to these uprights, as by means of welding or brazing, for forming a rigid structure. The front uprights extend preferably throughout the height of the piping and the rear uprights preferably extend throughout the 25 height of the coils of greater diameter.

The piping of the respective refrigerating elements is connected, as by means of a stretch of piping 82, extending from the top 30 of the piping of the refrigerating element 71 and slanting downwardly and rearwardly parallel with the slant of the upper doors 51, and having a lower rear portion 83 extending rearwardly into the cavity under the 35 wrapping counter, and extending into the corner 84 between said wrapping counter and the rear lower doors, the pipe extending thence as a longitudinal portion 85 in the angle between said wrapping counter and the main doors to a point in front of the 40 rear intermediate door post 32, which is behind the refrigerating element 72, the pipe continuing as a downwardly extending portion 86 and connecting with the lower end 45 of the piping forming the refrigerating element 72.

The refrigerating element 72 is formed similarly to the refrigerating element 71, with the exception preferably that a downwardly extending portion 87 extends from the rearwardly extending portion 83 of the 50 refrigerating element 72. This downwardly extending portion is located in line with the intermediate post 32 adjacent thereto. The 55 refrigerating element 71 may be provided with a feeding-in pipe 88, and the refrigerating element 72 may be provided with a feeding-out pipe 89. Suitable valves may be provided for the in-feeding and the out-feeding piping for regulating the amount 60 of refrigerant passing through the pipes. The refrigerant may have a flow indicated by the arrows 90.

The arrangement of the refrigerating elements is such that circulation of air is

caused in the case for subjecting all parts of the case to the cooling or refrigerating action of the refrigerating agents. The general course of the air currents adjacent to the refrigerating elements is downward and 70 then lateral at both sides of the refrigerating element, then upward, intermediate between the refrigerating elements in the wider or middle display section, and at the ends of the case, and then again lateral toward the refrigerating elements, whereby all parts of the case are subjected to the actions of the cooled currents. The general courses of the currents are indicated by the dotted arrows 91.

Goods supporting shelving is provided in the case, this shelving being exemplified as upper shelves 95, intermediate shelves 96, and lower shelves 97. The shelves are preferably formed perforate. The shelves 95 85 and 96 are shown formed of crossing wires rigidly secured together to form the shelves as rigid structures. These shelves are arranged at each side of the refrigerating elements, there being preferably two sections 90 for each shelf between the refrigerating elements, and one section for each shelf being preferably located between the respective refrigerating sections and the respective ends of the case. Each of the shelf sections is provided with an upwardly turned portion 98 adjacent to the refrigerating element, whereby the goods on the shelves are held out of contact with the refrigerating 95 elements.

The upper shelves 95 are supported at their rear ends in the angle of an angle iron 101, fixed to brackets 102, secured to the inner portion of the wrapping counter portion of the case. The shelves 96 are supported at 105 their rear ends in the angle of an angle iron 103, releasably held in clips 104, secured to the inner faces of the rear posts 31, 32.

The forward ends of said respective shelves are supported on angle irons 105, 110 106. One of the walls of said respective angle irons is received in clips 107, secured to the inner faces of the front intermediate posts 23 and end posts 22 of the display case, for placing said clips out of view of the 115 customer.

The angle irons 103, 105, 106, are respectively provided with openings 108 through which the hook portions of clips are received. The upright wall of the angle iron 120 is received between the hook portion and the body of the clip, which forms a slot, the walls of which hold the angle iron in angular position for support of the shelves thereon.

There is quite a long space between the front posts 23, and I prefer to reinforce the front angle irons spanning said space at intermediate points to prevent sagging of the same and to prevent forward bowing of the same, due to the weight and the force of 125 130

handling the goods on the shelves supported thereby. This is exemplified as accomplished by means of tension members 111, 112, 113, shown as chains.

6 The chain 111 is stretched between a hook 114 in the inner face of the central rear post 32 and the front angle iron 105, midway of the latter, to which it is secured, as by being hooked by means of a hook 115 through a 10 hole therein. The chain 112 is stretched between the angle iron 103 and the angle iron 106, the respective ends of the chains being hooked in holes in said respective angle irons. This chain is located under the chain 111. The chain 113 is supported at its top by means of a hook 116 secured in the top longitudinal rail 24 midway between the posts 23, and depends therefrom.

20 The chain 113 is secured to the chain 111 at the forward end of the latter by an interlacing connection 117, and to the forward end of the chain 112 by an interlacing connection 118, for suspendingly supporting the middle portions of the forward angle irons 105, 106. The flexible connections are 25 reusable, as by means of said hook connections from the case, and the front angle irons and the lower rear angle iron are removable, as by being raised out of their supporting 30 hooks.

If it is desired to clean the interior of the case, the shelf sections are raised from their supports and removed through the rear doors. The chains may also be released and 35 removed from the case, and the front angle irons and the lower rear angle iron may be raised off their supports and removed from the case, and conveniently cleaned and then replaced. The removal of these parts also 40 permits ready cleaning of the inner faces of the transparent closures at the front and ends of the case.

There is preferably one of lower shiftable shelves 97 for each of the rear main doors of the case. These shelves are formed of a 45 framework 119, to which separated slats 120 are fixed, the framework being provided with laterally extending flanges 121, riding on rollers 122, rotatable on axles 123, fixed in 50 runways 124, each comprising an upper angle iron 125 and feet 126 rigidly secured together, the feet being secured to the bottom of the case. The laterally extending wings 127 of the angle irons 125 are received 55 over the laterally extending flanges 121, the laterally extending flanges 121 sliding between said rollers and said wings 127.

These lower shelves are arranged to slide 60 outwardly through the door openings of the rear main doors 34, so that the goods thereon, which are usually the heaviest and bulkiest goods in the case, may be moved outwardly, so as to be readily handled by the attendant or salesman. These shelves are of a width 65 to conveniently pass through the door open-

ings when said doors are opened, and the pintles of the hinges 35 on which said doors are hung, are preferably laterally spaced from the margin of the door opening to permit the inner face of the door, which door is 70 usually thick and heavily heat insulated, to be in an out-of-the-way position with relation to the slideable shelf when the door is opened for access to said shelf.

The outward movement of these shelves is 75 also preferably limited to prevent the shelf under normal sliding relations to be moved out of its runways, and to insure that sufficient portions of the laterally extending flanges 121 are maintained between the rear 80 one of its supporting rollers and coacting wings 127, to prevent undue downward tilting of the rear end of the shelf. This is instanced as accomplished by providing the frame 119 with a lug 128, adjacent to its 85 front end, and the angle iron 125 with a coacting lug 129, adjacent to the rear end of the runway 124. The rearward sliding movements of each of the shiftable shelves 97 is limited by having its lugs 128 strike 90 the lug 129.

If it is desired to entirely remove the shelf, the rear end of the shelf is tipped upwardly, as indicated in dotted lines in Fig. 8, whereby the lug 128 on the shelf is tipped 95 downwardly into the space between the rear pairs of rollers, below the lug 129, moving the lugs or projections into non-interfering relations, and permitting the shelf to be removed from the case in tilted relations, as 100 for cleaning and other purposes.

Having thus fully described my invention, what I claim as new, and desire to secure by Letters Patent, is:

1. A refrigerator display case comprising 105 a base arranged to be supported on the floor and posts extending upwardly from the front portion of said base for dividing the front portion of the case into display openings arranged side by side lengthwise of the case, the upper portion of the rear wall of the case sloping forwardly to form an interior of the case which contracts cross-sectionally at its upper portion, and refrigerating elements provided with contracting 110 upper portions and arranged crosswise of the interior of the case in rear of said posts respectively and extending into said contracting upper portion of said interior for dividing said interior into display sections 115 in rear of said respective display openings. 120

2. A refrigerator display case comprising 125 a frame including a bottom adjacent the floor, a serving counter top, a wrapping counter at the rear portion of said frame lower than said serving counter, a display front extending from substantially said bottom to substantially said serving counter top, and slantingly arranged, slideable doors between said serving counter top and said 130

wrapping counter, and a refrigerating element extending crosswise in and substantially throughout the height of the interior of said frame and including a slantingly arranged upper portion in the level of said slantingly arranged slidable doors.

3. A refrigerating display case comprising a frame including a bottom adjacent the floor, a serving counter top, a wrapping counter at the rear portion of said frame lower than said serving counter, and a rear wall beneath the wrapping counter and forming an angle in the interior of said case with said wrapping counter, a plurality of upright refrigerating elements extending in spaced-apart relations crosswise in and substantially throughout the height of the interior of said frame and each comprising piping, and connecting piping between said refrigerating elements extending lengthwise in said angle.

4. A refrigerator display casing comprising a frame including a bottom adjacent the floor, a serving counter top, a wrapping counter at the rear portion of said frame lower than said serving counter top, a display front extending from substantially said bottom to substantially said serving counter top, doors between said serving counter top and the inner edge of said wrapping counter and forming an upper shallow interior portion of said display case above the horizontal plane of said wrapping counter, refrigerator doors in the rear wall of said frame under the rear edge of said wrapping counter and forming a lower deep interior portion of said display case, refrigerating elements arranged crosswise of the interior of said case in spaced-apart relation, dividing said interior into a plurality of goods compartments arranged side by side lengthwise of said interior and comprising end goods compartments and an intermediate goods compartment, and shelving at the respective sides of said refrigerating elements, said shelving located in the interior of said frame in substantially the horizontal plane of said wrapping counter, each of said refrigerating elements comprising a lower deep portion in said lower deep interior portion of said display case and extending under said wrapping counter, and an upper shallow portion extending above said shelving into said upper shallow interior portion of said display case.

5. A refrigerator display case comprising a frame including a bottom adjacent the floor, a serving counter top, a wrapping counter at the rear portion of said frame lower than said serving counter top, a display front extending from substantially said bottom to substantially said serving counter top, doors between said serving counter top and the inner edge of said wrapping counter and forming an upper shallow interior portion of said display case above the horizontal plane of said wrapping counter, refrigerator doors in the rear wall of said frame under the rear edge of said wrapping counter and forming a lower deep interior portion of said display case, refrigerating elements arranged crosswise of the interior of said case in spaced-apart relation, dividing said interior into a plurality of goods compartments arranged side by side lengthwise of said interior and comprising end goods compartments and an intermediate goods compartment, and shelving at the respective sides of said refrigerating elements, said shelving located in the interior of said frame in substantially the horizontal plane of said wrapping counter, each of said refrigerating elements comprising a lower deep portion in said lower deep interior portion of said display case and extending under said wrapping counter, and an upper shallow portion extending above said shelving into said upper shallow interior portion of said display case.

6. A refrigerator display case comprising a frame including a bottom adjacent the floor, a serving counter top, a wrapping counter at the rear portion of said frame lower than said serving counter top, a display front extending from substantially said bottom to substantially said serving counter top, doors between said serving counter top and the inner edge of said wrapping counter and forming an upper shallow interior portion of said display case above the horizontal plane of said wrapping counter, refrigerator doors in the rear wall of said frame under the rear edge of said wrapping counter and forming a lower deep interior portion of said display case, refrigerating elements arranged crosswise of the interior of said case in spaced-apart relation, dividing said interior into a plurality of goods compartments arranged side by side lengthwise of said interior and comprising end goods compartments and an intermediate goods compartment, and shelving at the respective sides of said refrigerating elements, said shelving located in the interior of said frame in substantially the horizontal plane of said wrapping counter, each of said refrigerating elements comprising a lower deep portion in said lower deep interior portion of said display case and extending under said wrapping counter, and an upper shallow portion extending above said shelving into said upper shallow interior portion of said display case.

In testimony whereof, I have hereunto signed my name.

GUSTAV SCHMIDT.
